COMBINATION LOCK

Henry Padleckas, 815 N. Oak Ave, Oak Park, Ill. 60302,
and Leonard Paulius, 6123 S. Bentley Ave., Clarendon
Hills, Ill. 60514

Filed Aug. 19, 1970, Ser. No. 24,568

Term of patent 14 years

Int. Cl. D8—06

U.S. Cl. D8—114

FIG. 1 is a top plan view of a combination lock showing our new design;

FIG. 2 is a side elevational view of the tumbler portion;

FIG. 3 is a side elevational view of the bolt portion thereof;

FIG. 4 is a top plan view of the bolt portion;

FIG. 5 is an end view of the tumbler portion taken substantially on line 5-5 of FIG. 2; and

FIG. 6 is a sectional view taken substantially on the line 6-6 of FIG. 2.

The cable end shown broken away indicates indeterminate length.

We claim:

The ornamental design for a combination lock, as shown and described.
